UNITED STATES PATENT OFFICE.

BERNICE J. NOYES, OF BOSTON, MASSACHUSETTS.

BUNSEN BURNER.

No. 806,827.

Specification of Letters Patent.

Patented Dec. 12, 1905.

Application filed April 23, 1904. Serial No. 204,562.

To all whom it may concern:

Be it known that I, BERNICE J. NOYES, of Boston, county of Suffolk, State of Massachusetts, have invented an Improvement in 5 Bunsen Burners, of which the following description, in connection with the accompanying drawings, is a specification, like characters on the drawings representing like parts.

This invention relates to Bunsen burners, 10 and has for its object to provide a specific form of Bunsen burner of the Welsbach type having adjustable gas-orifices with an adjustable air-shutter whereby the dimensions of the air-inlets may be varied.

15 The particular burner to which my invention is applied comprises, essentially, a tube having a plurality of side openings near its lower end adapted to receive upon it a support for the mantle and a support for the globe, a thimble contained in said tube having its top formed to constitute a diaphragm which is provided with a plurality of gas-orifices, said diaphragm being located in a plane with the side openings, an occluding- 20 plate mounted on said diaphragm adapted to open the gas-orifices more or less, a revolute actuating member for said occluding-plate adapted to be placed on said tube and consisting of a conical body having an engaging 25 portion for the occluding-plate and also having a perforated plate fixed to its lower end, through the perforations of which the air passes.

30 The air-shutter embodying my invention consists of an independently-movable perforated plate disposed in juxtaposition to the perforated plate which is fixed to the revolute actuating member for the occluding-plate, said movable perforated plate having a projecting finger-piece or other means whereby 35 it is moved independently of the fixed plate.

Figure 1 shows in side elevation a Bunsen burner embodying this invention. Fig. 2 is an enlarged vertical section of a portion of 40 the burner. Fig. 3 is a horizontal section of the burner, taken on the dotted line 3-3, Fig. 2. Fig. 4 is an under-side view of the revolute actuating member for the occluding-plate. Fig. 5 is a plan view of the perforated plate 45 which is located in juxtaposition to the perforated plate of the revolute actuating member and which is movable independently thereof. Fig. 6 is a detail to be referred to.

50 *a* represents a nipple having a threaded hole to receive the threaded end of the fixture and also having a threaded recess to receive

the tube *a'*, which is provided with a plurality of side openings *a²*, disposed in the same plane just above the top of the nipple *a*. The tube *a'* receives upon it a tube *b*, which bears a globe-support *b'* and also receives upon it the usual mantle. A thimble *c* is contained in the tube *a'*, the upper end of which is formed as a flat diaphragm *c'*, and said diaphragm is provided with a plurality of gas- 60 orifices *c²*, which are arranged in any suitable manner.

Upon the diaphragm *c* an occluding-plate *c³* is placed, which is pivoted to said diaphragm to be revolved thereon to open the gas-orifices 65 more or less. The occluding-plate has holes *c⁴* through it, which are brought into a position above the gas-orifices *c²*. The occluding-plate has a lug *c⁵* extended laterally from it, which is engaged by a revolute actuating member 70 for turning the plate. The revolute actuating member consists of a conical body *d*, having a perforated plate *d'* fixed to its lower end and having an engaging portion for the lug *c⁵*, consisting of a pair of vertical bars *d²*, 75 extending from the fixed plate *d'* to the top of the conical body, said bars receiving the lug *c⁵* between them. The revolute actuating member has a circular hole through it, whereby it is adapted to be placed upon and to quite 80 snugly fit the lower part of the tube *a'*. The fixed perforated plate *d'* has an entrance-slot *d³* for the lug *c⁵* opposite the space between the bars *d²*, so that the revolute actuating member may be placed upon the tube *a'* and the lug *c⁵* caused to occupy a position between the vertical bars *d²*.

e represents a circular perforated plate, which is herein shown as contained within the revolute actuating member and is placed upon 95 the fixed perforated plate *d'*. The plate *e* is held in place on the plate *d'* by overturning a lip *d⁴* on the fixed plate, or it may be otherwise held in place. The plate *e* is movable independently of the fixed plate *d'*, so that the 100 perforations thereof may be brought into position to register with the perforations of said fixed plate *d*, more or less, as desired, to thereby vary the size of the openings through which the air passes. The plate *e* has a downwardly-extended lug *e'*, which passes through a hole in the fixed plate *d'*—as, for instance, one of the air-holes—so as to be easily accessible, and by engaging said lug and exerting suitable pressure thereon the plate *e* will be 105 turned; yet it will be understood that the revolute actuating member is also free to be 110

turned to move the occluding-plate. The plate e has a slot e^2 , which may be moved into position to register with the slot d^3 to provide for the passage of the lug c^5 , when the revoluble actuating member is placed upon the tube a' .

I am aware that the occluding-plate and means for moving it, as herein shown, are not new, and, furthermore, I am aware that burners of the Welsbach type have been provided with adjustable air-shutters.

Having thus described my invention, what I claim as new, and desire to be secure by Letters Patent, is—

15 A Bunsen burner having a diaphragm provided with orifices, an occluding-plate rotatably mounted on said diaphragm having an outwardly-extended lug, a revoluble actuating member for said occluding-plate comprising

ing a conical body and a perforated plate fixed 20 to its lower end having an entrance-slot for said lug, and having a lug-engaging portion, and a perforated plate superimposed on the aforesaid fixed plate, having a lug projecting through an opening in said fixed plate for moving it independently of but with relation to said fixed plate, to vary the size of the air-inlets, and having a slot for the passage of the lug on the occluding-plate, which is adapted to register with the entrance-slot of the fixed 30 plate, substantially as described.

In testimony whereof I have signed my name to this specification in the presence of two subscribing witnesses.

BERNICE J. NOYES.
